UNITED STATES PATENT OFFICE

140,218

DESIGN FOR A BOMB RELEASING SHACKLE

Donald I. Sloan, Los Angeles, Calif., assignor to
Interstate Aircraft and Engineering Corp., a
corporation of California

Application April 22, 1944, Serial No. 113,339

Term of patent 14 years

(Cl. D71—1)

To all whom it may concern:

Be it known that I, Donald I. Sloan, residing at Los Angeles, in the county of Los Angeles, State of California, and a citizen of the United States, have invented a new, original, and ornamental Design for a Bomb Releasing Shackle, of which the following is a specification, reference being had to the accompanying drawing, forming part thereof.

In the drawing:

Fig. 1 is an elevational side view of a bomb releasing shackle showing my new design;

Fig. 2 is an inverted plan view of the bomb releasing shackle shown in Fig. 1; and

Fig. 3 is an end view of the bomb releasing shackle shown in Fig. 1.

Both sides of the device are similar except for the elongated rectangular plate member shown in the right central portion of Fig. 1.

I claim:

The ornamental design for a bomb releasing shackle, as shown and described.

DONALD I. SLOAN.
